COMBINED SPONGE AND SQUEEGEE WINDOW CLEANING DEVICE

Filed Oct. 20, 1949

INVENTOR.
Pratt R. Loveland
BY *Joshua R. Hause*
His Attorney

The object of employing a foraminous member 20 will be pointed out hereinafter.

The operation of the cleaning device 10 may briefly be described. The device is grasped by the handle 11, and the washing member 12 immersed in a bucket or pan containing suitable cleaning liquid, the pad 15 being compressed if desired to assure a maximum absorption of the liquid. The immersion and manipulation of the washing member to take up the cleaning liquid is readily effective by means of the handle, without requiring that the operator's hands engage in the liquid. The inner sash of a double-hung window to be cleaned is raised somewhat, and the washing member is inserted between the lower frame member of the outer sash and the pane of the lower sash, as illustrated in Figure 4. The operator's hand may readily grasp the bracing plate 19 and squeegee 16, which afford a broad gripping surface, so that the washing member may move back and forth without any rotation about the axis of the handle 11. After the window has been thoroughly wet and scrubbed by the pad 15, the device may be withdrawn from the position shown in Figure 4 and any liquid remaining in the pad may be removed therefrom by squeezing the same against a suitable surface, again merely by means of the handle. The use of a foraminous member 20, such as a perforated plate or the like, facilitates quick and complete discharge of liquid from the pad 15, as well as assists in the reverse absorbing process when it is desired to take up liquid in the pad.

The device may now be reversed, and the wiping member 13 inserted between the window sashes and employed to dry the window by removing the liquid previously applied to it. The plate 14 in this case serves as a gripping means for the handle 11 to aid in manipulating the squeegee 16 and maintaining it flat against the outer surface of the pane. It will be obvious that it is a relatively simple matter to draw the squeegee downwardly from the top of the sash to the bottom, remove any excess moisture thereon, and repeat the operation over a portion of the pane adjacent to that already wiped clear of liquid. The securement of the handle 11 on the inner face of the angle plate 19, it will be clear, reduces the overall thickness of the device 10 at the wiping or drying end thereof, while providing a stronger, rigid connection with the squeegee. The device may be used in a similar manner on the outer pane surface of the outer sash, although in this case it is not a matter of importance that the overall thickness of the device be held to any particular maximum. Thus it will be seen that the outer surfaces of double-hung sash may readily be cleaned by an operator standing safely within the building. Of course the inner surfaces may also be cleaned by the device of this invention, and the long handle 11 is an advantage particularly in connection with the upper sash, since it eliminates any need for standing on a support to reach the upper portions thereof. The perforated construction, with the pad 15 projecting outwardly of the periphery of the backing member, is advantageous in permitting the washer member to be moved into the angle between the pane and sash, and in fact squeezed therein, to assure removal of dirt from such a favorite lodging place. This construction also permits the pane from being scratched by the backing mem-

ber, and it may be pointed out that the provision of a grip at the other end of the handle to prevent canting of the washing member 12 relative to the window pane also assists in preventing such scratching.

It will of course be obvious that the washing member 12 may have a pad of other than sponge-like material, but in such case the device 10 would be less advantageous because absorption and discharge of cleaning liquid thereby would be more difficult, and in fact would probably require wetting of the operator's hands. Similarly, the squeegee 16 might be replaced by some other element for drying the window, which might be of a type which would absorb the liquid instead of wiping it off. Such a substitution is within the purview of my invention. Again, the wiping element might be omitted and a suitable grip member provided on the end of the handle 11 for proper manipulation of the washing member 12. The construction disclosed, however, is advantageous in that both the washing and drying members are always conveniently at hand when the device is employed, and further in that each of these members serves as a grip for the handle to assure proper manipulation of the other member.

Some changes which may be made in the disclosed embodiment of my invention without departing from the inventive concept have been indicated above, and others will readily suggest themselves. It is therefore not intended that the invention be limited otherwise than as required by the spirit and scope of the appended claim.

I claim:

In a cleaning device for double-hung sash windows, a handle in the form of a long, narrow, metallic, flat bar, a foraminous backing plate of substantially rectangular formation secured to one end of said handle in face to face engagement therewith, a pad of sponge rubber of rectangular formation similar to that of said backing plate, but of greater extent than said backing plate secured to the face thereof opposite to that to which said handle is attached, a bracing plate having two arms in angular relation, one arm of said bracing plate being secured to the other end of said handle in face to face engagement therewith, a channel member secured to the other arm of said bracing plate and assuming a longitudinal direction substantially parallel to the plane of said backing plate, and a rubber squeegee carried by said channel member.

PRATT R. LOVELAND.
